UNITED STATES PATENT OFFICE.

LOUIS KOSSUTH JOHNSON AND ABBOT AUGUSTUS LOW, OF BROOKLYN,
NEW YORK, ASSIGNEES TO THE ALDEN TYPE MACHINE COMPANY,
OF NEW YORK, N. Y.

TYPE-SETTING APPARATUS.

SPECIFICATION forming part of Letters Patent No. 596,598, dated January 4, 1898.

Application filed November 3, 1896. Serial No. 610,906. (No model.)

To all whom it may concern:

Be it known that we, LOUIS KOSSUTH JOHNSON and ABBOT AUGUSTUS LOW, citizens of the United States, residing in the city of Brooklyn, in the county of Kings and State of New York, have invented certain new and useful Improvements in Type-Setting Apparatus, of which the following is a specification sufficient to enable others skilled in the art to 10 which the invention appertains to make and use the same.

Our improvements relate to the class of compositor's type-case set forth in our concurrent applications, Serial Nos. 608,600, 608,578, and 15 609,652, in which the several types forming a word or other combination of characters are forwarded from the lower end of a containing-channel, means being provided for adapting the device to the forwarding of different 20 words or combinations by the relative adjustment of the parts. Heretofore the types have been forwarded onto a type-platform in front of the channel, by which platform they have been restricted in their movement during 25 withdrawal by hand, necessitating care on the part of the compositor in withdrawing them over the type-platform in a plane parallel thereto. In our present application we dispense with the type-platform, confining the 30 advanced types entirely between the under surface of the presser-foot and the upper edge of a yielding type-finger on the trigger-lever, so that the types, while fully sustained until wanted, readily adapt themselves to the fingers of the compositor and may be withdrawn at various angles. This enables the compositor to work more rapidly and conveniently, and also reduces the wear on the types.

Another feature of our invention consists 40 in regulating and prescribing the position of the type-containing channel in its holder from beneath the supporting-table by means of a channel-supporting screw which is adjustable with relation to a fixed front guard on the 45 holder and with relation to a blade-pusher having a fixed path of reciprocation. By this means we simplify the construction of the channel-holder, doing away with the adjustment of the front guard thereon, and are en-

abled to effect the adjustment of the parts to 50 the requirements of different words and combinations without the removal of the channel, its holder, or the type-pusher. In this connection our invention also includes a special form of flexible type-finger on the trigger-lever whereby the finger is made adjustable 55 in inclination as well as in height.

In the accompanying drawings, Figure 1 is a plan of a series of channels, holders, &c., constructed according to our invention. Fig. 2 is a vertical section upon plane of line 2 2, Fig. 1; Fig. 3, a front elevation; Fig. 4, a detail view of the type-finger; Figs. 5 and 6, sectional elevations showing the parts adjusted for different words or combinations of types. 65 Figs. 7 and 8 are detail views of the removable end of the trigger-lever.

The table or support A is formed with the sockets a, into which the tenons h of the holders H fit, as described in our prior applications 70 hereinbefore referred to. The front guard h' and its presser-foot h² form a permanent part of the holder H, as do the side walls h³ h⁴ and back h⁵. The extension of the side wall h³ forms the tenon h, while the opposite 75 wall h⁴ extends down to and rests upon the top of the table A.

The type-containing channel C is formed with the type-shoulder c, leaving the slot c' on one side for the passage of the pusher-blade P, the spine of the channel and the back of the holder being also slotted, as heretofore, to accommodate the pusher-blade.

The pusher-blade P is of maximum height, say, for seven types, and is supported and 80 reciprocated by any of the means heretofore described by us.

The bottom of the type-containing channel C rests upon the upper end of an adjusting-screw S, passing through the table A and having a jam-nut s, by which it is set after its adjustment to the height desired. The lower end of the screw S is square to engage with a key, or is otherwise formed to facilitate the adjustment of the screw.

It is obvious that other mechanical expedients may be substituted for the screw to afford an adjustable support upon the table for

the type-containing channel, although we prefer the screw on account of its simplicity and economy of space.

The trigger-lever T is constructed and arranged to control the type-forwarding mechanism substantially as heretofore described by us, its novelty in the present case consisting in the fact that it is provided with a flexible type-finger F, which is adjustable both in height and inclination.

The base f of the type-finger is formed with the longitudinal slot f', through which passes the stem of the thumb-screw f².

f³ is the flexible type-bearing pivoted to the base f at f⁴ and having its lower arm held normally against a stop f⁵ by a spring f⁶.

The position of the type-floor c of the channel having been set with relation to the pusher P and to the presser-foot h² by means of the screw S or its equivalent, the base f is adjusted on the end of the trigger-lever T, so as to rest against the under side of the types when forwarded, as will be understood by reference to Figs. 5 and 6, the slot f' admitting of both the vertical and lateral adjustment of the type-finger. In order to render the action of the type-finger still more sensitive, we in some cases pivot the forward end of the trigger-lever so that in its normal position it is held in alignment by a spring t', acting against the shoulder or stop f². Thus the finger-piece will yield vertically in case of undue pressure. The spring t' also holds the type-finger against the types with a gentle yielding pressure.

As the channels are necessarily close together to economize space horizontally, the spaces between the ends of adjoining trigger-levers are so slight that the adjustment of the type-finger vertically by means of the set-screw f³ cannot be conveniently effected while the finger-lever is in place, and for this reason we make the extreme forward end t³ of the trigger-lever removable, as by dovetailing its shank t⁴ into the hinged portion t or by other suitable means.

What we claim as our invention, and desire to secure by Letters Patent, is—

1. In a compositor's type-case the combination of a type-containing channel, a holder, stationary front guard and presser-foot, a type-forwarding blade having a prescribed path of reciprocation, and means for supporting the type-channel independent of its holder and for adjusting the said channel with relation

to the prescribed path of the reciprocating forwarding-blade for the purpose and substantially in the manner described.

2 In a compositor's type-case the combination of the type-channel C, formed with the type-floor c, the channel-holder H, formed with the fixed front plate and presser-foot h², the type-forwarding blade P, having a prescribed path of reciprocation, and the screw S, for supporting the channel C, adjustably from below and independent of the holder, substantially in the manner and for the purpose described.

3. In a compositor's type-case the combination of the type-containing channel, channel-holder, supporting-table and type-forwarding mechanism, of a front guard and presser-foot projecting beyond the front edge of the supporting-table, and a type-finger situated in front of said supporting-table and acting in conjunction with the presser-foot above, and a trigger-lever acting in conjunction with said front guard and presser-foot, substantially in the manner and for the purpose described.

4. In a compositor's type-case, the combination of a type-containing channel, channel-holder, type-forwarding mechanism, of a trigger-lever formed with a jointed finger-lever held in its normal position by spring-pressure substantially in the manner and for the purpose described.

5. In a compositor's type-case substantially such as described, the combination of a finger-lever mounted upon the stem t', having the shank t⁴, and the trigger-lever T, formed with the recess for the reception of the shank t⁴, substantially in the manner and for the purpose described.

6. The combination with the type-channel, channel-holder with stationary front guard and presser-foot, and with type-forwarding mechanism, of the trigger-lever T, and adjustable type-finger consisting of the base f, formed with the slot f', and secured to the lever T, by thumb-screw f², the pivoted bearing f³, stop f⁵, and spring f⁶, the whole arranged and operating substantially in the manner and for the purpose described.

LOUIS KOSSUTH JOHNSON.
ABBOT AUGUSTUS LOW.
